PISTON COOLING IN FREE-PISTON UNITS

Walter A. Ledwith, Hartford, Conn., assignor to
 United Aircraft Corporation, East Hartford,
 Conn., a corporation of Delaware

Application March 27, 1945, Serial No. 585,160

16 Claims. (Cl. 123—176)

1

This invention relates to free-piston units and particularly to an arrangement for circulating a cooling fluid through the piston assemblies.

Fluid has been circulated through the racks which form a part of the synchronizing linkages, since these racks are connected to a part of the piston assemblies. Although this arrangement is satisfactory, in many cases the coolant may leak and affect the supply of lubrication to the linkage. A feature of this invention is an arrangement for maintaining a circulation of coolant through the piston assembly independently of the synchronizing mechanism.

During the reciprocation of the piston assemblies, the inertia forces acting on the coolant within the piston are such that coolant will normally flow into the piston during part of the piston stroke and will tend to discharge from the piston during the remainder of the stroke. To assure a flow of coolant, it may be necessary to provide valves to prevent the inertia forces from causing an undesirable flow of the coolant. A feature of this invention is an arrangement by which the valves are opened and closed by the piston movement.

Another feature is an incorporation of the valves as an integral part of the coolant circulating system.

In using telescoping tubes for delivering the coolant to or discharging it from the piston, the stationary tube is normally secured at one end only in order to permit the moving tube on the piston to reciprocate. The tubes may, during operation, become so out of line that they bind or do not function satisfactorily. A feature of this invention is the use of a through tube which may be supported at both ends and over which the piston reciprocates. Another feature is the arrangement of the tubes for controlling the flow of coolant into and out of the piston.

In using telescoping tubes for admitting fluid to the piston it has been customary to use the variable volume within the tubes to cause a pumping action by which the coolant is circulated through the piston. At high speed, the inertia forces acting on the coolant in the piston may oppose this pumping action to such an extent that undesirably high pressures develop in the coolant system. A feature of this invention is an arrangement of the coolant tubes in such a manner that the inertia forces are utilized to assist the coolant circulation instead of opposing it.

Other objects and advantages will be apparent from the specification and claims and from ac-

2

companying drawings which illustrate an embodiment of the invention.

Fig. 1 is a sectional view through the free-piston unit.

5. Fig. 2 is a sectional view through a piston assembly.

Fig. 3 is a sectional view through the coolant outlet device.

10 Fig. 4 is a fragmentary sectional view showing the arrangement of the valve in the coolant inlet device.

Fig. 5 shows a modified form of coolant tube.

Fig. 6 is a sectional view through one end of 15 the unit, substantially at right angles to the section of Fig. 1.

The unit shown includes an engine cylinder 10 having reciprocating pistons 12 and 14 to which compressor pistons 16 and 18 in cylinders 20 and 22 are integrally connected. Sleeves 24 and 26 20 attached to the compressor pistons complete the reciprocating piston assembly. The sleeves in combination with stationary pistons 28 and 30 form air spring cylinders.

The pistons are moved apart by the burning of 25 fuel injected into engine cylinder 10 through one or more nozzles 32. Air compressed in the air spring cylinders on the power stroke returns the piston assembly. The pistons are always maintained at equal distances from the center of the 30 engine cylinder by a linkage which may include racks extending from the piston assemblies and meshing with a pinion, not shown.

Intake manifold 42, which extends around the compressor and engine cylinders, conducts air to 35 intake valves 44 in the heads of the compressor cylinders, through which air automatically enters at opposite ends of the cylinders. Compressed air leaves the cylinders through discharge valves 46, also at opposite ends of the compressor cylinders and passes into a center scavenging chamber 48 and end chambers 50 and 52. These chambers may be connected by a scavenging manifold, not shown.

40 Compressed gas from the scavenging chambers enters engine ports 54 and 56 which are uncovered by pistons 12 and 14 at the end of the power stroke, thereby permitting air to be blown through the engine cylinder. Gas in the engine cylinders is discharged through exhaust ports 58 45 into exhaust manifold 60.

The compressor cylinders may be unloaded by 53 the use of rows of spill ports 63 in the cylinder walls. The effective volume of the compressor cylinders is determined by the number of rows of spill ports that are closed. This structure is

claimed in the copending application of Cooper Serial No. 531,301.

As shown in Figs. 2 and 6, the piston assembly has a passage 62 in the compressor piston 18 which communicates with a tube 64 positioned centrally within the engine piston 14. Coolant passing through the tube 64 is discharged into a space 65 between the engine piston and a shield 66 positioned within the engine piston. This space is connected by passages 68 and a radial passage 70 with the fluid discharge.

As shown in Fig. 3, the coolant outlet device includes a tube 72 extending from a bracket 74 which may be integral with the wall 76, Fig. 1, of the center scavenge chamber 50. The other end of the tube is supported in a bracket 78 integral with the end cap 80 that forms the scavenge chamber 52.

The ends of the tube are supported by packings 82 and 84 in the brackets 74 and 78 respectively. These packings allow a slight radial movement of the tube, and they may also permit expansion of the tube both radially and axially resulting from changes in temperature of the coolant.

Surrounding the tube 72 is another tube 86 supported centrally by the compressor piston 18, being locked in place by a clamping ring 88. This tube has passages 90 communicating with the passage 70 in the compressor piston. The ends of this tube 86 slide within seals 92 and 94 in the inner and outer heads 96 and 98 of the compressor cylinder and, as shown, tube 86 is short enough to permit reciprocation over the tube 72 without engaging the packings 82 and 84.

From a point adjacent to the center of the compressor cylinder 22 to a point adjacent the outer cylinder head 98, the tube 72 is reduced in diameter to form a chamber 100 between tubes 72 and 86. Ports 102 permit flow of coolant into the tube from the chamber 100 and communicate with the end of passage 90 during approximately the outer half of the stroke of the compressor piston.

The inertia of the coolant within the piston is used to cause it to flow out of the piston. During approximately the last half of the outward stroke of the piston assembly, the deceleration of the piston assembly causes coolant to flow toward the outer (right hand, Fig. 2) end of the space 65 and to discharge through passages 68, 70 and 90 into the chamber 100, and thence into tube 72. From tube 72 coolant discharges through a conduit 104 connecting with a passage 106 in a cap 108 on the bracket 78.

During approximately the first half of the inward piston stroke, the inertia forces act on the coolant to cause it to discharge from the piston along the same path. On the last half of the inward piston stroke and the first half of the outward stroke the accelerations are such that the coolant flows toward the head of the piston so no discharge of coolant will take place; during this part of the stroke chamber 100 is out of communication with ports 90 and the discharge passage is thus closed.

The supply of fluid to the piston is controlled by a similar pair of tubes, 110 and 112. For the inlet tube, the reduced portion 114 which forms a chamber 116 extends from approximately the center of the compressor cylinder to a point adjacent with the inner cylinder head 96. Thus coolant may flow into the piston from tube 110 only during the latter half of the inward stroke of the piston or the first half of the outward stroke,

During approximately the last half of the inward stroke of the piston assembly, the piston assembly is decelerating and the inertia forces on the coolant cause it to flow toward the head of the piston and thus permit flow of coolant into the piston at a low pressure. Also, during approximately the first half of the outward stroke, the coolant also flows toward the piston head by reason of the inertia forces so that coolant may be admitted at a low pressure during this time.

It will thus be apparent that the piston coolant outlet is open during the part of the piston stroke when the inertia forces on the coolant will cause a discharge of the fluid from the piston, and the inlet is open when the inertia forces are reversed and will permit a flow of coolant into the piston.

The coolant tubes thus act as conduits through which coolant may flow into and out of the piston but do not, in themselves perform any pumping. When coolant tubes of the conventional type are used, the pumping action of the telescoping tubes must take place in spite of the inertia forces on the coolant in the piston. The present arrangement of through tubes eliminates this pumping action and permits the flow to occur as a result of the inertia forces on the coolant.

The space surrounding tube 72 at each end, that is, the space between the seals 82 and 92 and the space between the seals 84 and 94, may be enclosed and connected to a drain. As shown, a sleeve 118 surrounds tube 72 between bracket 74 and the cylinder head 96 and may be held in place by a clamping ring 120 which holds the sleeve in the bracket. The space within the sleeve 118 may be connected to a drain through a passage 122.

At the opposite end of tube 72, a sleeve 124 surrounds the tube 72 and is held in place by a clamping ring 126. This sleeve together with a cylindrical opening 128 in head 80 collects any coolant escaping between the tubes. This space may be connected to a drain by a conduit 130.

Instead of a continuous through tube such as the tubes 72 and 110 it may be advantageous for the purpose of eliminating restrictions to the coolant flow, that the coolant be supplied through spaced tubes 132 and 134 as shown in Fig. 5. The adjacent ends of the tubes are spaced apart an amount corresponding to the length of the reduced portion of the tube 72 and the tubes fit inside of a sleeve 136 corresponding to either of sleeves 100 or 112. With this arrangement of separate tubes it may be advantageous to support the tubes against axial movement as, for example, by a projecting flange 138 on the outer end of tube 134. This flange fits between the bracket 140 corresponding to the bracket 78 and a cap 142 mounted on the bracket. A sealing ring 144 may be used to prevent leakage around the end of the tube. The arrangement of ring 144 may be such that it will permit a slight lateral movement of the tube, the flange 138 being slightly smaller than the opening in the bracket to provide for such movement.

It is to be understood that the invention is not limited to the specific embodiment herein illustrated and described, but may be used in other ways without departure from its spirit as defined by the following claims.

70 I claim:

1. In a free-piston unit having a reciprocating piston, cylinders in which the piston reciprocates, coolant tubes extending from one of the cylinders in parallel relation to the piston reciprocation, and tubes mounted in the pistons for reciproca-

tion with said pistons and fitting over the coolant tubes.

2. In a free-piston unit having a reciprocating piston, cylinders in which the piston reciprocates, coolant tubes extending from one of the cylinders in parallel relation to the piston reciprocation, and tubes mounted in the pistons for reciprocation with said pistons and fitting over the coolant tubes, said piston having a passage communicating with the tubes mounted in the piston.

3. In a free-piston unit having a reciprocating piston, cylinders in which the piston reciprocates, coolant tubes extending from one of the cylinders in parallel relation to the piston reciprocation, and tubes mounted in the pistons for reciprocation with said pistons and fitting over the coolant tubes, said piston having a passage communicating with the tubes mounted in the piston, and means for delivering coolant to one of said coolant tubes.

4. In a free-piston unit having a reciprocating piston, cylinders in which the piston reciprocates, coolant tubes extending from one of the cylinders in parallel relation to the piston reciprocation, and tubes mounted in the pistons for reciprocation with said pistons and fitting over the coolant tubes, the coolant tubes being constructed to admit coolant from one of the tubes to the piston and to admit coolant from the piston into the other tube.

5. In a free-piston unit having a reciprocating engine piston, a cylinder in which the piston reciprocates, and a compressor cylinder and piston, the latter being connected to and moving with the engine piston, a coolant tube mounted at least at one end in the compressor cylinder and extending through the compressor piston, and a tube mounted in the compressor piston and fitting over the coolant tube.

6. In a free-piston unit having a reciprocating engine piston, a cylinder in which the piston reciprocates, and a compressor cylinder and piston, the latter being connected to and moving with the engine piston, a coolant tube mounted at least at one end in the compressor cylinder and extending through the compressor piston, and a tube mounted in the compressor piston and fitting over the coolant tube, said piston having means for delivering coolant from the coolant tube to the engine piston.

7. In a free-piston unit having a reciprocating engine piston, a cylinder in which the piston reciprocates, and a compressor cylinder and piston, the latter being connected to and moving with the engine piston, a coolant tube mounted at least at one end in the compressor cylinder and extending through the compressor piston, and a tube mounted in the compressor piston and fitting over the coolant tube, said coolant tube being constructed to provide a connection from said tube to the surrounding tube mounted in the piston during a portion only of the piston reciprocation.

8. In a free-piston unit having a reciprocating engine piston, a cylinder in which the piston reciprocates, and a compressor cylinder and piston, the latter being connected to and moving with the engine piston, a coolant tube mounted at least at one end in the compressor cylinder and extending through the compressor piston, and a tube mounted in the compressor piston and fitting over the coolant tube, said coolant tube having a passage therethrough, and said piston having a cooperating passage through which coolant flows.

9. In a free-piston unit having a reciprocating engine piston, a cylinder in which the piston reciprocates, and a compressor cylinder and piston, the latter being connected to and moving with

5 the engine piston, a coolant tube mounted at least at one end in the compressor cylinder and extending through the compressor piston, and a tube mounted in the compressor piston and fitting over the coolant tube, said coolant tube having

10 a passage therethrough, and said piston having a cooperating passage through which coolant flows, said passages being arranged to provide for a circulation of coolant during a portion only of the piston reciprocation.

15 10. In a free-piston unit having a reciprocating engine piston, a cylinder in which the piston reciprocates, and a compressor cylinder and piston, the latter being connected to and moving with the engine piston, a coolant tube mounted at

20 least at one end in the compressor cylinder and extending through the compressor piston, and a tube mounted in the compressor piston and fitting over the coolant tube, said coolant tube having a reduced portion extending approximately from the midpoint of the compressor cylinder to a point adjacent one head of the cylinder, thereby providing for flow of coolant through the tube during a portion only of the piston reciprocation.

11. In a free-piston unit, engine and compressor cylinders, a piston assembly including engine

30 and compressor pistons fitting in the cylinders, said engine piston projecting from one side of the compressor piston and having a chamber therein through which coolant may circulate,

35 passages in said compressor piston communicating with said chamber, and tubes extending through the compressor piston and parallel to the direction of reciprocation of the piston assembly, the passages in the compressor piston

40 communicating with these tubes, in combination with coolant tubes mounted in the compressor cylinder and cooperating with the tubes in the piston to form an extensible duct through which coolant may be delivered to or discharged from the piston assembly.

12. In a free-piston unit, engine and compressor cylinders, a piston assembly including engine and compressor pistons fitting in the cylinders, said engine piston projecting from one side of

50 the compressor piston and having a chamber therein through which coolant may circulate, passages in said compressor piston communicating with said chamber, and tubes extending through the compressor piston and parallel to the direction of reciprocation of the piston assembly,

55 passages in the compressor piston communicating with these tubes, in combination with coolant tubes mounted in the compressor cylinder and cooperating with the tubes in the piston to form an extensible duct through which coolant may be delivered to or discharged from the piston assembly, said coolant tubes extending through the tubes on the piston.

60 13. In a free-piston unit, engine and compressor cylinders, a piston assembly including engine and compressor pistons fitting in the cylinders, said engine piston projecting from one side of the compressor piston and having a chamber therein through which coolant may circulate,

65 passages in said compressor piston communicating with said chamber, and tubes extending through the compressor piston and parallel to the direction of reciprocation of the piston assembly, the passages in the compressor piston

70 communicating with these tubes, in combination with coolant tubes mounted in the compressor cylinder and cooperating with the tubes in the piston to form an extensible duct through which coolant may be delivered to or discharged from the piston assembly.

75 14. In a free-piston unit, engine and compressor cylinders, a piston assembly including engine and compressor pistons fitting in the cylinders, said engine piston projecting from one side of the compressor piston and having a chamber therein through which coolant may circulate, passages in said compressor piston communicating with said chamber, and tubes extending through the compressor piston and parallel to the direction of reciprocation of the piston assembly, the passages in the compressor piston

with coolant tubes mounted in the compressor cylinder and cooperating with the tubes in the piston to form an extensible duct through which coolant may be delivered to or discharged from the piston assembly, said coolant tubes extending through the tubes on the piston, and being supported at least at one end in the compressor cylinder.

14. In a free-piston unit having a reciprocating engine piston, a cylinder in which the piston reciprocates, and a compressor cylinder and piston, the latter being connected to and moving with the engine piston, coolant tubes mounted at least at one end in the compressor cylinder and extending through the compressor piston, and tubes mounted in the compressor piston and fitting over the coolant tubes, said coolant tubes having a reduced portion extending approximately from the midpoint of the compressor cylinder to a point adjacent one head of the cylinder, thereby providing for flow of coolant through the tube during a portion only of the piston reciprocation, one of said coolant tubes being the inlet tube and being constructed to communicate with the inlet passage in the piston during approximately the inner half of the stroke of the piston.

15. In a free-piston unit having a reciprocating engine piston, a cylinder in which the piston reciprocates, and a compressor cylinder and piston, the latter being connected to and moving with the engine piston, coolant tubes mounted at least at one end in the compressor cylinder and extending through the compressor piston, and tubes mounted in the compressor piston and fitting over the coolant tubes, each of said coolant tubes having a reduced portion extending approximately from the midpoint of the compressor cylinder to a point adjacent one head of the cylinder, thereby providing for flow of coolant through the tube during a portion only of the piston reciprocation,

one of said tubes being the inlet tube and being constructed to communicate with the inlet passage in the piston during approximately the inner half of the stroke of the piston, and the other coolant tube being the outlet tube and being constructed to communicate with the outlet passage in the piston during approximately the outer half of the stroke of the piston assembly.

16. In a free-piston unit, an engine cylinder, a compressor cylinder, a piston assembly including engine and compressor pistons reciprocating in said cylinders, a pair of stationary coolant tubes extending from one of the cylinders in parallel relation to the direction of piston reciprocation, said tubes extending through openings in the compressor piston, and sleeves mounted over the coolant tubes and supported by the compressor pistons, an inlet and an outlet passage in the compressor piston, and a coolant chamber in the engine piston with which said passages communicate, said passages extending from the sleeves to the chamber, in combination with means forming a part of the coolant tubes to provide for the admission of coolant through one of the tubes to the chamber in the engine piston during a part only of the piston stroke and for the discharge of coolant through the other of the tubes from the chamber during substantially the remainder of the stroke of the piston assembly.
